UNITED STATES PATENT OFFICE.

CLARENCE FANCHER, OF HUDSON FALLS, NEW YORK.

CUTTING TABLE.

Application filed February 26, 1923. Serial No. 621,377.

To all whom it may concern:

Be it known that I, CLARENCE FANCHER, a citizen of the United States, residing at Hudson Falls, in the county of Washington and State of New York, have invented certain new and useful Improvements in Cutting Tables, of which the following is a specification.

This invention relates to what may be termed devices especially adapted for severing or dividing up drawing linen or paper into the usual required sized pieces or sheets to meet the wants or conveniences of the draftsman in the drafting room and the trade in keeping the same in stock for sale.

The invention has for its object, among other things, to carry out these ends with facility, simplicity and inexpensively; to provide against "miss-cuts" and accordingly wastage of drawing-linen or paper; to provide for gauging the depth of the penetration of the severing instrumentality or knife in cutting the material or linen, as well as to provide for the assured straight-cutting thereof.

Other objects of the invention will be apparent together with the foregoing, from the following further disclosure of the invention.

The invention therefore consists of certain instrumentalities and features of construction substantially as hereinafter more fully disclosed and pointed out by the appended claims.

In the drawing accompanying the following specification and disclosing the preferred embodiment or one form of my invention it will be understood that various changes and modifications as relate to the detailed construction and arrangement of parts may be made without departing from the spirit of my invention as covered by the appended claims and in which drawing

Fig. 1 is a broken plan view of the device disclosing the embodiment of my invention, parts being broken away.

Fig. 2 is a longitudinal section taken through the drawing-linen or paper holding clamps.

Fig. 3 is a similar vertical section taken through the device at right angles to the line of Fig. 2.

Fig. 4 is a detached perspective showing a clamp with its resilient or spring retaining member.

Fig. 5 is a like view as relates to the trac-

ing linen or paper clamp, a screw and lever member however, substituting the clamp retaining resilient or spring member.

As characteristic features of my invention, I employ a plurality or number of sections 1, preferably of smooth plane boards or panels having under and over projecting interfitting edges. These sections are rectangular in general outline and assembled for mutual cooperation, being hinged together as at 2, preferably along their longitudinal edges at suitable points or at the extreme ends upon alternate opposite sides thereof, whereby they (said sections) may be, and are thus adapted to fold compactly upon each other as disclosed for ready shipment or storage. These sections or resultant leaves forming what is termed a table, are further hinged, or rather the lateral or side ones, at their ends, as at 3, to transverse end member 3^a, the connections or hinging being effected therebetween upon the same sides of the end members 3^a and the corresponding or end leaves 1. The leaves are arranged so as to provide therebetween narrow longitudinal and transverse spaces 8 and 9 traversing each other, respectively, throughout, which provides for the insertion thereinto, of say a "pocket" knife, and the suitable severing of the tracing linen or drawing paper into the required sized sheets accordingly, as may be provided for by the relative graduation apart of the spaces.

Suitably constructed or shaped clamps with penetrating points on under side 10 are arranged or secured at the end of the leaves or members 1^a of the table and when clamped down the points penetrate the linen or tracing cloth as shown, which is clamped down and effectively held thereon, the under projecting points securely holding the linen when making the final cuts, the linen or tracing cloth being carried initially over the members 4 and under the clamps when raised, as shown. The clamps, themselves, are suitably held in position by means of resilient member 11 suitably secured to the table and adapted to allow the clamps to be elevated and automatically held thereby as indicated in dotted lines when initially applying and securing the linen or tracing cloth upon the table, the clamps, of course, being sprung down in holding position upon the tracing material by suitably tripping the resilient members, as seen in the disclosure.

The table leaves or sections, it will be noted, are stepped at their initial adjacent edges as at 12 to provide for limiting the extent of the penetration of the tracing-linen severing knife and thus provide for maintaining a straight cut of said edges, otherwise stated to obviate a miss-cut or miss-cuts, as previously stated.

The modified form of clamp-retaining device, designated as 13, in Fig. 5 comprises, as above indicated, a screw-threaded body member 13^a suitably threaded preferably into one of the hinge leaves or sections and having a handle or arm 13^b which is adapted, by suitably grasping and turning the same so as to cause it to suitably frictionally engage the upper surface of the clamp, whereupon said arm or handle will produce a binding action thereon and thus secure the clamp in effective or locked position. It is to be understood, of course, that my table or device as herein described in detail or requiring the use of expedients in carrying out the same is not restricted or limited 25 as relates to the breadth and scope of the claims, to any additional appendage or means of support therefor in facilitating the utilizing the same, although such may be shown in connection with the drawing or implied by the description as may be read into the specification.

I claim:

1. A device of the type described, comprising a sectional table whose sections or leaves are hingedly or foldably assembled together, with intermediate lines of spaces between said leaves or sections extending transversely and longitudinally throughout the same whereby a cutting member may be inserted within said spaces and drawn along the same.

2. A device of the type described, comprising a sectional table whose sections or leaves are hingedly or foldably assembled together with intermediate lines of spaces between said leaves or sections extending transversely and longitudinally throughout the same whereby a cutting member may be inserted in said spaces and drawn along the same, said table also being portable.

3. A device of the type described, comprising a table formed of a plurality of leaves or sections hingedly connected together at alternate opposite sides with intermediate lines of spaces therebetween extending transversely and longitudinally throughout the same whereby a cutting member

may be inserted in said spaces and be drawn along the same.

4. A device of the type described comprising sectional table whose sections or leaves are hingedly or foldably assembled together, with intermediate lines of spaces extending longitudinally and transversely throughout, the adjacent walls of said sections or leaves being stepped, whereby a cutting member may be inserted within said spaces to be drawn therealong, but the depth of penetration of the cutting member will be limited by the stepped edges.

5. A device of the type described, including a table comprising a plurality of sections, with a plurality of longitudinal and transverse straight line spaces therebetween, said sections being hingedly or foldably assembled together, clamps with penetrating points on under side applied to said leaves or sections for the retention of the work to be operated upon in position thereon, and means for holding said clamps in place upon said table.

6. A device of the type described comprising a table formed of a plurality of sections hingedly or foldably and portably assembled together, said sections or leaves being arranged to provide longitudinal and transverse spaces therebetween and having their walls formed with interfitting steps which are to be spaced apart, said spaces being adapted for the insertion therein of an instrumentality for severing the work laid upon the table to be operated upon as said instrumentality is passed into said spaces.

7. A device of the character described comprising a table formed of a plurality of sections hingedly connected together so as to be folded to form a portable structure, the sections having their walls oppositely stepped and fitted together so as to leave a space between each section and its neighboring sections, whereby a cutting member may be inserted within the spaces thus formed and drawn therealong to sever the work laid upon the table, the stepped portion of the sections serving to limit the depth to which the cutting member may penetrate, transverse strips hingedly connected to certain of the sections, clamps arranged upon said strips and having penetrating points to retain the work laid upon the table and tensioning means cooperating with said clamps.

In testimony whereof I affix my signature.

CLARENCE FANCHER.
